BUNDLING STRAP

George Geisinger, Elizabeth, N.J., assignor to The Thomas & Betts Co., Elizabeth, N.J., a corporation of New Jersey

Filed July 19, 1965, Ser. No. 86,197

Term of patent 14 years

(Cl. D17—5)

FIGURE 4 is a top plan view of the bundling strap with its tail end portion in looped relation to the head-end portion thereof showing the manner of laying the narrow portion of its tail end in an open slot formed in the head-end thereof; and

Portions of the design shown in FIGURES 1, 2 and 3 are shown broken away to indicate indefinite length.

I claim:

The ornamental design for a bundling strap, as shown and described.
